R. A. BREDOV

HAT BLOCK

Filed April 26, 1926

INVENTOR:
Robert A. Bredow,
BY *Joshua Shelley*
ATTORNEY.

UNITED STATES PATENT OFFICE.

ROBERT A. BREDOV, OF LOS ANGELES, CALIFORNIA.

HAT BLOCK.

Application filed April 26, 1926. Serial No. 104,725.

The present invention relates to hat blocks, such as those used in blocking hats, hat forms and the like, and the invention is applicable to hat blocks heated electrically or otherwise and used in connection with manual locking means or hat blocking machines.

One of the objects of the invention is to provide a manually operated hat block adapted to be used in connection with a suitable heating element, such as an electric heating element.

Another object of the invention is to provide an improved hat block which may be used in connection with hat blocking machines.

Another object of the invention is to provide a hat block adapted for manual operations, apart from a machine, which will increase the speed of production and render the operations more efficient and expedient.

Still other objects of my invention will appear hereinafter.

I have illustrated my invention by the accompanying drawings, in which:—

25 Figure 1 is a view in elevation of a preferred embodiment of my invention.

Figure 2 is a view in bottom elevation of a part hereinafter known as the block.

30 Figure 3 is a plan view of the device shown in Fig. 1, with the block removed.

Figure 4 is a vertical section of the embodiment shown in Fig. 1, showing material formed about the block in the final stage of blocking a hat.

35 The various purposes for which a hat block is used; such for instance as shaping buckram forms, forming, pressing, cleaning and blocking hats, are well understood and need no description herein.

40 The following specification relates to the construction of the said embodiment and the salient features of my invention, which provide for more rapid and efficient use of such hat blocks.

45 More specifically, 8 indicates the part hereinafter known as the hat block, and consisting, in this embodiment, of a hollow dome shaped block open at the bottom, as at 9. The bottom of the block is provided with a horizontal annular flange 10, provided with slots or openings 11, breaking into said flange.

The base is indicated by the numeral 12 and may form a part of a complete hat blocking machine (not shown), or may be adapted to be secured to a table or like article 14, by

means of the legs and feet 15 and 16, respectively, and screws 17. In conformity with a salient feature of my invention, said base includes an upper integral horizontal plate 19, 60 provided with a central opening 18 through which a heating element 20 projects, so that the heating element stands above the plate and projects into the hollow space 21, enclosed by the block 8. The heating element 65 is preferably of upright cylindrical form of the luminous type, such as are used in electric "glow" heaters. Such form and disposition of heating element provide for sending the heat by radiation, principally, to all inside surfaces of the block equally.

The top of the auxiliary base is formed with a plate 19^a, similar to the top of the base. Said plate is provided with a central aperture 18 through which the heating element 70 75 75 projects. The bottom of the auxiliary base is provided with a horizontal annular flange 10^a, similar to the flange of the bottom of the block.

Both the plates 19 and 19^a are provided with a vertical circularly described interrupted rim 22 and 22^a, respectively, so arranged that the inside margins 23, of a flange, such as 10 or 10^a, will be guided thereby in a circular motion. Both vertical rims 80 85 include radially projecting members 24 and 24^a, respectively, conforming in size and spacing to the slots 11, and each projecting member is arranged to extend over the corresponding one of flanges 10 or 10^a, to hold 90 the members in assembly, as shown in the cross section.

To attach the auxiliary base to the lower base, the slots in the flange of the auxiliary base are aligned with the projections on the lower base. The auxiliary base is lowered over the lower base until the flange of the auxiliary base rides on the plate of the lower base. Subsequently the auxiliary base is revolved a few degrees on the lower base until the major axis of the auxiliary base is aligned with the major axis of the lower base. When so turned, the auxiliary base cannot be lifted or dislodged from the lower base until one is turned relative to the other to bring the 105 slots into registration again with the corresponding projections.

The block proper is adapted to be connected with the auxiliary base in the same manner as the auxiliary base is connected with the lower base. Therefore, the block may be attached directly to the lower base 110

in case occasion arises where the auxiliary base is not used.

The block and auxiliary base each terminate in a sharp or square edge, as at 25, while the lower base and the auxiliary base are each beveled so as to provide string grooves 26 and 26^a, respectively. The string groove 26 comes immediately below the edge 25, while the string groove 26^a, comes immediately below the edge 25^a.

When the heating element is energized, the block and the lower base, if the latter is employed, are thoroughly heated by radiation from the heating element. In shaping the material, such as 29, over the block, said material may be secured by a string 30, which draws the material quite taut over the block. The string may be placed in either groove. In the case of some materials it is advisable to allow the shape to dry while it is in place over the block. This may be done by removing the block and auxiliary base jointly from the lower base while said block and auxiliary base are connected to each other. By inverting the removed assembly the atmospheric air has access to the interior of the block and same will cool rapidly. In other cases it may be advisable to leave the assembly in place upon the base, but ordinarily the retained heat of the removed assembly will provide for curing the material even after such assembly is removed. When the material is properly dried, the auxiliary base is removed from the block, and the string, without means to hold it in place, automatically slides from the block and does not need to be untied or removed by hand. By using the auxiliary base and block in conjunction, in the manner just described, one heating element and lower base will serve for several hat blocks, and rapid progress may be made.

Inasmuch as the parts are quickly detachable from each other, a change may be made from one block to another quite readily and without necessity for handling hot screws, bolts or the like. The lower sharp edged block gives a defined lower margin 32 to the shaped material, so that the excess material therebelow may be accurately removed. Obviously, the string may be placed in the lower groove in the case of making a deeper hat or form, in which case removal of the auxiliary base will result in automatic dislodgment of the string. In cases where the

device is needed only occasionally, the auxiliary base is not needed; the lower block being left on the lower base until the finished product is finally removed.

Where the base is a part of a hat block machine, it is proposed to attach the block and a lower base to each other and employ the auxiliary base for holding the string in place after the assembly of auxiliary base and block is removed from the lower base. Other obvious combination uses and other advantages of the arrangement of parts shown will suggest themselves to the minds of those skilled in the art.

It will be apparent now that I have provided an efficiently heated electric hat block, which in the case of hand work or machine work will speed up the production of blocked hats, forms and the like, and which provides for allowing a hat or shape to dry while tied to the hat block while the base and heating element are being used in conjunction with another block and auxiliary base.

While I have shown and described a specific embodiment of my invention, I do not limit myself to any specific construction, embodiments, or arrangement of parts, and I may alter same as I desire or as occasion demands, and I may use any construction or arrangement of parts coming within the scope of the appended claims.

I claim:

1. In a hat blocking device, a lower base, an auxiliary base detachably connected to said lower base, and a hat block detachably secured to and above said auxiliary base; the complete device providing two annular string grooves; one string groove being at the juncture of said block and auxiliary base and the other string groove being at the juncture of said auxiliary base and said base.

2. In a hat blocking device, a lower base, an auxiliary base detachably connected to said lower base, and a hat block detachably secured to and above said auxiliary base; the complete device providing two annular string grooves; one string groove being at the juncture of said block and auxiliary base and the other string groove being at the juncture of said auxiliary base and said base; those portions of said block, auxiliary base and lower base, respectively, which are adjacent the string grooves, being of the same cross section.

ROBERT A. BREDOW.
